UNITED STATES PATENT OFFICE.

FREDERICK R. L. STOTT AND THOMAS CROSSEN, OF HAMILTON, ONTARIO, CANADA.

HANDLE FOR AIR-BRAKE VALVES FOR RAILWAY-CARS.

1,035,490.

Specification of Letters Patent.

Patented Aug. 13, 1912.

Application filed October 27, 1910. Serial No. 589,396.

To all whom it may concern:

Be it known that we, FREDERICK R. L. STOTT and THOMAS CROSSEN, both subjects of the King of Great Britain, and residents 5 of Hamilton, in the county of Wentworth and Province of Ontario, Canada, have jointly invented new and useful Improvement in Handles for Air-Brake Valves for Railway-Cars, of which the following is a specification.

10 Our invention relates to improvements in safety handles for air-brake valves, for railway cars, and consists of a key, or wrench, secured to the valve, and a pressure controlled safety handle fulcrumed to said key adapted to open, close and to lock the valve.

15 The objects of our invention are, first to provide a safety handle on a rotatable valve adapted to rotate the same in opposite directions, and which can not effect said rotary motion without first bringing the handle, in other, or non-rotary direction by pressure, in order to effect said rotary motion; second, to provide safety means on a rotatable valve 20 adapted to rotate the same in opposite directions and which can not be compelled to effect said rotary movement without first bringing said safety means, by pressure, in other, or non-rotary direction to effect said

25 rotary movement, under any circumstance or condition to which the valve may be subjected, third, to provide a safety handle on a rotatable valve adapted to rotate said valve and to lock the same together with 30 the handle in opposite directions, and which can not be unlocked by any jars, or vibration, or by the forcible changing of position of the valve while air-tubes are being coupled thereto or uncoupled therefrom, there- 35 40 by preventing possible accidents.

We attain these objects by the mechanism illustrated in the accompanying drawing, in which:—

45 Figure 1 is an elevation of an air brake safety handle on the shank end of a rotatable valve in a casing, or angle cock used on railway cars in general and in locking position, said handle shown in raised position by broken lines. Fig. 2 is a plan of the same 50 showing the position of the safety handle in broken lines when the same is rotated in raised, and also in lowered and locked position. Fig. 3 is a plan of the top of the casing or angle-cock of the valve, showing 55 the common rectangular shank of the valve in section, the shank extends through said

top, and is shown in broken vertical lines in Fig. 1 of the drawing. Fig. 4 is a plan of the handle together with its key, or wrench, detached from the valve, the outer part of 60 said key, together with its mechanism being in section. Fig. 5 is a detail elevation of a portion of the detached handle. Fig. 6 is a detail plan of a portion of the detached key or wrench. Fig. 7 is a detail plan of a portion of the detached handle. 65

Similar letters refer to similar parts throughout the several views.

In the drawing, the casing or angle-cock, for railway cars, is indicated by A, and B is 70 the rectangular shank of the valve and extends upward and beyond the top of the casing in the usual manner of valves, to receive a key, or wrench, to rotate the valve in opposite directions, that is, to open and 75 to close the valve. The ends 2 and 3 of the casing or angle cock, are adapted to receive air-tubes coupled thereto in the usual manner, and said casing is generally located on the ends of railway cars which have air- 80 brakes connected thereto. The top of the casing has projecting shoulders 4 and 5 shown in Fig. 3, the shoulders 4 and 5 are not new.

C is the safety handle, and D, is the key, 85 or wrench, to which the handle is fulcrumed. The key D has a rectangular opening 6 adapted to fit onto the shank B, and to rest on the top of the cock, and extending from said key is a cylinder 7, and a jaw 8, in 90 alinement with said cylinder. The opposite end of the handle C has an arm, or lug 9, adapted to fit between the end of the cylinder and the jaw 8, and is fulcrumed on the bolt or pin 10, which extends through the 95 jaw 8, the lug 9, the cylinder 7, and the end nut 12, which is secured in the cylinder. The pin 13 extends through the cylinder, the nut and the bolt, to secure said parts together. The opposite end of the bolt 10 has 100 a head 14, the several parts being shown in Fig. 4, of the drawing.

S, is a spiral spring coiled around the bolt 10, between the jaw 8 and the nut 12, one end of the spring is inserted in a notch, or recess 15, formed in the lug 9 of the arm, and the opposite end of the spring is inserted in a similar notch, or recess 16 in the nut 12, and when said nut is rotated sufficiently and thereby to impart proper tension to the spring, the pin 13 is then inserted to position. The end of the spring 110

engaging with the lower and outer, or rear part of the lug 9, of the handle, tends to lift said part, thereby pressing the handle firmly and heavily on the key D, the opposite end of the spring presses in the notch 16. The spring may be further tensioned, to have more power, by rotating the nut 12, after the pin 13 is withdrawn. The underside of the lug 9 of the arm, shown in Figs. 10 and 5, has an extension 17 which is adapted to engage with the underside of the key D, immediately between the jaw 8, and the cylinder 7, thereby preventing the handle from being lifted too high.

15 18, is a stop extending from and below the key and is a part of the key. 19 and 20 are similar stops extending from and below the key C, and form a part of the key. The stops 19 and 20 are in about diametrical line 20 one with the other, and the similar stop 18 of the key, is in circumferential line about midway between said stops 19 and 20. When the valve is open, as shown, the stop 18 of the key, contacts with the shoulder 4, of the 25 valve casing, shown in Fig. 3, and simultaneously the stop 19, contacts with the shoulder 5. The handle is there locked by the tension, or pressure, on the handle, caused by the spring.

30 To close the valve, the stops 19 and 20 must be freed from the shoulders 4 and 5 of the valve casing, this is accomplished by lifting the handle on its fulcrum, by manual strength, until the stops 19 and 20 are higher 35 than the shoulders 4 and 5 of the casing. The handle is shown in broken lines in this lifted position in Fig. 1. The handle may then be rotated together with the key to a position shown in broken lines in Fig. 2, 40 and the handle allowed to fall to position. At this changed position of the handle and key, to close said valve, the stop 18, of the key contacts with the shoulder 5, and the stop 20, contacts with the shoulder 4, and 45 there stops. At this time the arm, the key and the valve, are locked by the inherent tendency of the handle to press on the key. The key is secured to the valve shank B, by means of a pin 21, which extends through 50 said shank and key, as is usual.

It will be noticed that the valve can not be rotated in either direction, without first lifting the properly tensioned handle, sufficiently to allow the stops on the handle to 55 escape the shoulders of the cock.

The stop on the key and a stop of the handle are arranged to snugly fit between the shoulders of the valve casing thereby

preventing the valve from rotating in either direction.

60

Should the valve casing be upside down, or in any unnatural position caused by being jolted while traveling, or by adjusting or coupling air-tubes connected therewith, the shank of the valve will not be moved in consequence, thereby avoiding possible accidents.

Other mechanical means, other than shown, may be employed to tension the safety handle so as to bear heavily on the 70 key.

What we claim as our invention and desire to secure by Letters Patent, is:—

1. In an air brake valve, the combination with a casing having separated shoulders, of a rotatable valve in the casing which is provided with a shank, a key secured to the shank and provided with a member adapted to play between and to be limited in its movement by the shoulders aforesaid, said key being provided at one side of its connection with the shank with a cylindrical casing, a handle pivoted to the key, a torsion spring contained within the cylindrical casing and engaged therewith and with the handle and adapted to hold the handle down on the key, said spring being housed and protected by the cylindrical casing, and means on the handle adapted to engage the shoulders.

90

2. In an air brake valve, the combination with a casing having separated shoulders, of a rotatable valve in the casing which is provided with a shank, a key secured to the shank and provided with a member adapted to play between and to be limited in its movement by the shoulders aforesaid, said key being provided at one side of its connection with the shank with a cylindrical casing, a bolt extending longitudinally through the cylindrical casing, a torsion spring contained within and housed and protected by the cylindrical casing and surrounding the bolt, an adjustable nut on the bolt with which the said spring is engaged whereby its tension may be regulated, and a handle pivoted on the bolt and engaged with the spring whereby the spring holds the handle down on the key, said handle having a member adapted to engage the shoulders aforesaid.
